MIXING APPARATUS

Jacob A. Lavine, Chicago, Ill.

Application April 26, 1938, Serial No. 204,434

3 Claims. (Cl. 259—75)

The present invention relates to novel and improved mixing apparatus. While a preferred embodiment of the said apparatus, as hereinafter disclosed, is particularly well adapted for use by druggists in connection with the intimate admixing of fluids and the like in the preparing and filling of prescriptions, it will be evident that the mixing apparatus may also be readily employed in the admixing of other materials.

10 A primary object of the invention is to provide a relationship of parts which, in association, produces a compact, but reliable and efficient mixing apparatus which is portable in character and may readily be accommodated in the relatively crowded quarters of the average drug store laboratory.

It is further within the purview of the present invention to make the constituent parts of the apparatus of a character such that they may be 20 readily disassembled for the purpose of replacing or exchanging particular parts when, for any reason, this is found to be necessary or desirable.

As will hereinafter appear, the present invention provides a relatively uncomplicated and 25 commensurately inexpensive unit which may be conveniently operated wherever a supply of electric current is available.

Briefly stated, the new and improved apparatus comprises essentially a source of power, 30 an oscillator including means for securely retaining thereon a receptacle adapted to contain the ingredients to be admixed, and means for interconnecting the said source of power with the said oscillator. The latter means is preferably of such character, according to the invention, as to be capable of converting relative rotary power from the source of power, which may take the form of a small electric motor, into relative oscillatory movement at the oscillator. This means, 35 moreover, is preferably of a construction such as to counterbalance any tendency of the motor shaft toward whipping or excessive vibration due to the conversion of the rotary movement into oscillatory movement. Electric power for actuating the motor may preferably be obtained by means of a conventional plug which may be associated with a conventional electric outlet. The specific details of the above outlined general relationship of parts is described in detail in the 40 following specification proper.

Other objects and advantages of the apparatus according to the invention will be apparent to those familiar with the art to which the invention belongs, from the following detailed description 45 thereof, particular reference being made to the

preferred exemplary embodiment illustrated on the accompanying sheets of drawings.

On the said sheets of drawings:

Fig. 1 is a top plan view of an assembly of parts constituting a preferred form of mixing apparatus in accordance with the concept of this invention;

Fig. 2 is a front elevational view of the apparatus shown in Fig. 1;

Fig. 3 is a view of the oscillator and associated 10 parts, taken along line 3—3 of Fig. 2 and viewed in the direction of the arrows;

Fig. 4 is a top plan view of the adjustable base of the oscillator assembly;

Fig. 5 is a sectional view taken along line 5—5 15 of Fig. 4; and

Fig. 6 is a bottom plan view of the base of Figs. 4 and 5.

Corresponding elements are designated by corresponding reference characters throughout the 20 several figures of drawings.

Referring now to the drawings, reference character 10 designates a base member which constitutes a common support for the parts comprising the mixing apparatus so that the latter may be 25 transported as a unit. This base member 10 may be removably affixed to any supporting member such as a laboratory table or the like in any suitable and/or desirable conventional manner, such for example as by means of bolts or clamping 30 members or the like.

Securely mounted on base 10 are, on the one hand, a small electric motor 11, and on the other hand, an oscillator assembly 12, the latter being interconnected with the motor through the 35 medium of member 13.

The electric motor 11 may be of any suitable and/or desired conventional size and type, and may preferably be supplied with electric current through conduit 14 which terminates in a conventional plug for plugging into the usual electric outlet. Base 10 is preferably also provided with a suitably interconnected switch 15 whereby 40 operation of the device may be conveniently controlled at the base.

The oscillator assembly, according to the preferred illustrated embodiment of the invention, comprises essentially an upright wall member 16, a horizontal clamp supporting arm 17 which may conveniently consist of a lateral extension at 50 the top of vertical wall member 16, and an adjustable receptacle supporting platform which also extends laterally from the wall member 16 in the same direction as arm 17.

Wall member 16 is provided along each side 55

thereof with a rearwardly extending flange 18, the flanges 18 and wall 16 defining therebetween a slideway, the purpose of which will herein-after appear. The lower end of wall 16 merges 5 into a downwardly directed perforated extension 19 which preferably is coplanar with the wall itself, but is somewhat narrower than the latter.

The journal bearing on which the oscillator is arranged for oscillatory movement may assume the form of a pair of spaced perforated ears 20 extending upwardly from a common base plate 21 which is bolted or otherwise securely fixed to base 10. Extension 19 of wall 16 is received, as shown in Fig. 2 of the drawings, 15 between ears 20, with the perforations of the latter in alinement with each other and with the perforation of the said extension so that a pivot bolt 22 may extend therethrough and be held in place by nut 23 or the like.

20 The container which holds the ingredients to be agitated or intimately admixed with the aid of the present apparatus is intended to be positioned in the space defined by wall 16 at one side, arm 17 at the top and the platform at 25 the bottom. The container will, of course, rest on the platform. In order that the container may be securely clamped in place, arm 17 is provided with an adjustable screw clamping bolt 24.

30 The platform consists of a supporting plate 25 with a rubber covering 26. Plate 25 is flanged at each side thereof and these flanges 27 are extended rearwardly in the form of arms 28. Extending inwardly from each arm 28 is a lug 29. Lugs 29 are adapted to be received in dentations 30 formed on the rear edge of flanges 18 as shown. The space between lugs 29 is such that they can be passed over the relatively narrow member 19 to be positioned in dentations 35 30. The container supporting platform is thus pivotally and adjustably supported on wall 16.

Downward pivotal movement of the platform is limited by rod 31 which extends between flanges 27. Rod 31 is preferably so positioned relatively 45 to the other parts that it bears on the front of wall 16 when the platform is in place, the latter being horizontally disposed when the rod 31 is in contact with the wall. It will be apparent from the foregoing that when the platform is moved upwardly at its outer end, rod 31 is disengaged from wall 16, so that lugs 29 50 may be disengaged from the dentations 30 upon which they happen to be resting and may be moved into engagement with another set of dentations. The platform may thus be adjusted as a whole in accordance with the size of the container to be accommodated thereon.

To cooperate with clamp 24 in retaining the container on the oscillator member, the platform may further comprise a lateral retainer. This may take the form of a slide 32 which fits 60 beneath plate 25, the outer end of slide 32 being deformed to provide a pair of spaced upwardly extending retainer tongues 33 with a handle 34 therebetween. Slide 32 is provided with a substantially central longitudinal slot 35 which is traversed by a headed pin 36 integral with and depending from the lower surface of plate 25. The slide bears upon and is supported by the 65 head of the said pin 36.

As will be clear from the drawings, slide 32 70 may be moved out from the platform (to the right in Fig. 2) for the purpose of increasing the effective container supporting area or surface. Retainer tongues 33 are kept in snug con-

tact with the outer surface of the container by the action of spring 37 which is secured at one end to projection 38 which is struck downwardly from slide 32, and to the middle of rod 31 at the other end. Handle 34 may be used in withdrawing the slide as well as in raising the outer end of the platform when adjusting the position thereof on dentations 30.

In order to transmit movement from the shaft 39 of the electric motor 11 to the oscillator assembly 12 while simultaneously converting the rotary movement of the shaft into oscillatory movement of the oscillator assembly, use is preferably made of a double eccentric member 13. 15

The latter consists essentially of a sleeve portion 40 which fits tightly and concentrically on shaft 39, as shown in Fig. 3. Any suitable and desirable conventional means may be used for securing member 13 on shaft 39. Sleeve 40 terminates at each end thereof in an eccentrically 20 disposed cam member 41, one of which fits snugly into the slideway formed by wall 16 and its flanges 18.

To counteract any tendency to undue vibration or whipping of the relatively high speed motor 25 shaft 39, it is preferred according to this invention to dispose the cam members 41 in such manner that they extend from sleeve 40 in diametrically opposite directions, as is clearly illustrated in Fig. 2 of the drawings. This opposed positioning of the cams balances them and eliminates 30 tendency of the shaft to vibrate and whip.

It will be evident that the described construction is such that, upon rotation of 39 and of associated member 13, cams 41 will also rotate and such rotation will effect oscillation of member 12 about pin 22 as a pivot, thus producing the desired agitation of the contents of the container mounted in the oscillator assembly and effecting intimate admixture of the ingredients of such contents. 40

As has previously been noted, the aforescribed detailed description is directed to a presently preferred form of the invention. It is evident, however, that various slight changes in details may be effected without departing from the spirit or scope of the invention. Accordingly, the disclosure as herein set forth is intended to be primarily illustrative and not limitative, the invention being restricted solely by the terms of the definitive claims 50 hereunto appended.

What is claimed is:

1. A receptacle-holding assembly particularly adapted for use in mixing apparatus of the class wherein a receptacle is oscillated from a source of rotary motive power through the medium of means for converting said rotary power into oscillatory movement, said assembly comprising a wall, a top and a platform defining a receptacle receiving space, means for adjustably pivotally associating said platform with said wall, said means including a series of lug-receiving dentations on said wall and a pair of lugs on said platform arranged in said dentations, and means on said platform for preventing relative downward pivotal movement of said platform beyond horizontal position, said lugs being dissociable from said dentations and displaceable relative thereto upon upward pivotal movement of said platform. 55

2. A receptacle-holding oscillatory assembly comprising a vertical wall, flanges on said wall defining a slideway associable with means for imparting oscillatory motion to said assembly, said flanges being provided with a series of aligned dentations on the rear edges thereof, a platform 60

extending laterally from said wall and comprising lugs adapted to be received in a pair of aligned dentations, means on said platform adapted to engage said wall for holding said platform in horizontal position relative to the wall, said lugs being moveable from one set of dentations to another upon disengagement of said holding means, a top extending laterally from said wall, said wall and top and platform defining a receptacle receiving space, means on said top for exerting holding pressure downwardly on the receptacle, and means on said platform for exerting holding pressure on said receptacle in another direction.

15 3. A receptacle-holding oscillatory assembly comprising a vertical wall, flanges on said wall defining a slideway associative with means for imparting oscillatory motion to said assembly, said flanges being provided with a series of aligned

dentations on the rear edges thereof, a platform extending laterally from said wall and comprising lugs adapted to be received in a pair of aligned dentations, means on said platform adapted to engage said wall for holding said platform in horizontal position relative to the wall, said lugs being movable from one set of dentations to another upon disengagement of said holding means, a top extending laterally from said wall, said wall and top and platform defining a receptacle receiving space, means on said top for exerting holding pressure downwardly on the receptacle, and means on said platform for exerting holding pressure on said receptacle in another direction, said last-named means comprising spring-pressed tongue members extending upwardly from said platform in a direction substantially parallel with said vertical wall.

10 15 JACOB A. LAVINE.
